Primary Examiner — R. Johnson(57) **CLAIM**

The ornamental design for a kids drum set, as shown and described.

DESCRIPTION

FIG. 1 is a front, right and top perspective view of a kids drum set showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged, partial view taken at line 9 in FIG. 1. The broken lines in the figures illustrate portions of the kids drum set that form no part of the claimed design.
